CHARLES A. BREWER, OF NOROTON HEIGHTS, CONNECTICUT, ASSIGNOR TO CANNON ENGINEERING CO., OF BROOKLYN, NEW YORK, A CORPORATION OF NEW YORK.

ELECTRIC STEAM PRESSING IRON.

Application filed October 24, 1924. Serial No. 745,592.

This invention relates, generally, to improvements in electrically heated steam pressing irons provided with means for automatically regulating and controlling the operation of the heating means.

The invention has for its principal object to provide in combination with a pressing iron having means to extravasate steam from its pressing face, an electrical heating means provided with a thermostatic control for automatically maintaining the heat of the iron body at a desired predetermined temperature, whereby the steam delivered through the iron is guarded, on the one hand, against undue temperature drop likely to result in the formation of water by condensation, while, on the other hand, excessive temperature rises likely to result in superheating the steam and thus causing excessive pressure are likewise avoided.

The invention has for a further object to provide, in connection with an electrically heated steam iron of the type having a combined water separator and secondary steam generator through which steam from a suitable primary source is passed prior to delivery into the main steam chamber of the iron, a separate or independent continuously operating electric heating means for uninterruptedly supplying heat to the combined water separator and secondary steam generator.

Other objects of this invention, not at this time more particularly enumerated, will be clearly understood from the following detailed description of the same.

With the various objects of this invention in view, the same consists, primarily, in the novel electric steam pressing iron herein-after set forth; and the invention consists, furthermore, in the several novel arrangements and combinations of the various devices and parts, as well as in the details of the construction of said parts, all of which will be hereinafter more fully described in the following specification, and then finally embodied in the claims appended thereto.

The invention is clearly illustrated in the accompanying drawings, in which:—

Figure 1 is a vertical longitudinal section through the iron made according to and embodying the principles of the present invention; Figure 2 is a transverse section taken on line 2—2 in Figure 1; and Figure 3 is a wiring diagram illustrating the electrical

circuits through the heating elements of the iron.

Similar characters of reference are employed in all of the hereinabove described views to indicate corresponding parts.

Referring now to said drawings, the reference character 1 indicates the main body of the pressing iron, the same being cast from a suitable metal, so as to provide on its under side a smooth pressing face 2. The body 1 of the iron is cored to provide an internal steam chamber 3 entering its heel or rear end and extending longitudinally forward toward the toe thereof. The body of the iron, intermediate its pressing face 2 and the steam chamber 3, is provided with a plurality of suitably spaced and disposed steam vents or openings 4 leading from said steam chamber to the pressing face of the iron. The body 1 of the iron is further provided at its upper side or top, and above said steam chamber 3, with a countersunk seat or recess 5, preferably corresponding in shape to the peripheral outline of the iron. Disposed in said seat or recess 5 is an electrical heating unit 6 of any suitable construction, and provided with current conducting wires or other conductive elements 7 which are suitably imbedded therein. The heating unit 6 is retained in engagement with the bottom of the seat or recess 5 by means of a keeper plate 8 of any suitable construction, and suitably secured to the body of the iron by any desired form of fastening means, such e. g. as screws 9.

To enclose the heating unit 6 and associate parts, there is provided a top-casing 10, which is suitably shaped to conform to the outline shape of the iron, as well as to close over said heating unit and associate parts. The peripheral upper margin of the iron body 1 is provided with an inwardly off-set peripheral shoulder 11 adapted to provide in conjunction therewith a peripheral seat 12. The marginal edge portions of the top-casing 10 are telescopically engaged over said peripheral shoulder 11, with the free edge of the former seated upon or abutting the peripheral seat 12, thus holding the top-casing against lateral displacement. The top-casing 10 is secured against separation or vertical displacement from assembled relation to the iron body in any manner and by any means found to be convenient or desirable.

A suitable handle bail or arch 13, of any desired shape, is secured by rivets 14, or otherwise, to the top-casing 10 so as to be disposed longitudinally of the iron. Said bail or arch 13 is provided with a suitable hand-grip member 15. Secured intermediate the top-casing 10 and the hand-grip member 15, in any suitable manner, is a heat resistant shield 16, adapted to intercept heat radiated from the top of the iron, and thus shield the hand of the user from the uncomfortable effects of radiated heat when the iron is being manipulated.

The top-casing 10 is provided at its rear end, behind the bail and hand-grip member, with an upwardly projecting casing extension 17, for purposes subsequently to be described.

The reference character 18 indicates the combined water separator and secondary steam generator with which the iron may be equipped, the same comprising a suitably shaped metallic casting which is suitably secured to the heel of the iron body 1 so as to extend upwardly therefrom. Said casting is cored to provide a substantially vertical internal chamber 19, which serves both as a trap for condensed water and as a boiler chamber in which the trapped condensed water is reconverted into steam subject to delivery into the main steam chamber 3 of the iron body. Provided in the upper free end of said casting is an internally threaded opening leading into the upper end of said combined trap and boiler chamber 19, in which is engaged a bushing 20 adapted to support a steam-intake pipe 21, which extends downwardly within said chamber 19 so as to terminate intermediate the upper and lower ends thereof. Connected with the outer end of said steam-intake pipe 20, by a suitable union device 22, is one end of a flexible steam conduit 23 which leads from a main or primary source of steam supply. Said chamber 19 is closed at its bottom end by a partition or wall 24 which separates the interior of the chamber 19 from a discharge orifice 25 with which the lower end of the casting is provided. Extending upwardly through said partition or wall 24 is a steam discharge pipe 26, the open intake end 27 of which terminates within the upper end of said chamber 19, while its lower discharge end communicates with said discharge orifice 25.

When the casting which forms the combined water separator and secondary steam generator 18 is operatively assembled with the heel of the iron body 1, it closes the rearward open end of the steam chamber 3 of the latter, and the discharge orifice 25 of the former is properly aligned with said open end of the steam chamber 3. Supported by a bushing 28, which is engaged

in the outer end of said discharge orifice 25, or otherwise connected and supported in communication with the latter, is a hollow steam distributing member 29, which extends longitudinally forward through the interior of the steam chamber 3 of the iron. Said steam distributing member 29 is perforated at its underside to provide a plurality of steam delivery orifices 30. Suitably supported within said steam chamber 3, so as to be aligned with, and so as to enclose said steam distributing member, is a tubular water trap member 31 of enlarged diameter, the same having steam discharge vents 32 in its sides. The steam issuing from the distributing member 29 first passes into the interior of the trap member 31, and thence issues through the discharge vents 32 of the latter into the steam chamber 3 of the iron body 1 for extravasation through the vents 4 to the pressing face of the iron. Any condensation of water from the steam is caught in the bottom side of the trap member 31, and is thus prevented from accompanying the steam into the steam chamber 3 and thence through the vents 4 on to the goods being pressed by the iron.

Said casting, which forms the combined water separator and secondary steam generator 18, is provided in its inner or forward wall with a recess or seat 33, which is located opposite the lower end of the chamber 19. Secured within this recess or seat 33 is an electric heating unit 34 of any suitable construction, and provided with current conducting wires or other conductive elements 35. Said recess or seat 33 is closed by a cover plate 36, which serves to retain the heating element or unit 34 in place. If desired, a heat-resistant sheet 37 of asbestos, or other material, may be interposed between the heating unit 34 and cover plate 36.

Connected with the free end of said casing extension 17, are male contact plugs or terminals, comprising a positive plug or terminal 38 and a negative plug or terminal 39. The same being each secured by bolts 40 and nuts 41, the former of which extend upwardly from the interior of said casing extension 17 through the wall thereof so as to engage the bases of said plugs or terminals. An open ended shield or enclosure 42 may be assembled with the plugs or terminals to protect the same from blows or the like. The respective plugs or terminals 38 and 39 and their fastening bolts 40 are insulated against electrical contact with the casing extension 17 and the shield or enclosure 42 by means of washers and sleeves of insulation material 43. The inner ends of the bolts 40 with their nuts 41, and assisted by metallic washers 44, serve also as binding posts for attaching circuit wires operatively in connection with the respective plugs or terminals. The positive conductor

45 for the secondary steam generator heating unit 24, is connected between washers 44 on the bolt 40 connected with the positive plug or terminal 38, and extends therefrom, 5 through an opening 46 in the rear wall of said casing extension 17, to and through the cover plate 36 for connection with one pole of said heating unit 34; while the negative conductor 47, which is connected with the 10 opposite pole of said heating unit 34, passes outwardly through the coverplate 36, thence inwardly through the opening 46, for connection between washers 44 on the bolt 40 connected with the negative plug or terminal 39, thus coupling the electrical service circuit between the plugs or terminals 38 and 39 and said heating unit 34.

Supported by a bracket piece 48 secured to the top-casing 10, or otherwise supported 20 in any desired convenient manner, is an automatic electrical thermostatic switch or cut-out, the same comprising a pair of parallel contact arms rigidly secured together at their rear ends in desired spaced apart 25 relation by an intermediate spacing block 49 of insulating material. The contact arms and spacing block 49 are secured in supported connection with said bracket piece 48 by a bolt and nut 50, which is electrically 30 separated from electrical engagement with the respective contact arms by insulation 51. One of said contact arms, preferably the upper of the pair, constitutes an adjustable contact arm 52, provided adjacent to its free 35 end with a contact button 53, and an upwardly extending threaded shank or adjusting screw 54. The other of said contact arms constitutes a thermostatic contact arm 55 consisting of superimposed layers of 40 metals having respectively different coefficients of expansion, whereby the same will flex or bend from a normal contact making position when expanded by heat. The free end of said thermostatic contact arm 55 is 45 provided with a contact button 56 which normally engages, in circuit closing relation, with the contact button 53 of the adjustable contact arm 52. The means for adjusting 50 said adjustable contact arm 52 comprises a bushing 57 of insulating material mounted in the end wall of the casing extension 17, and in which is supported a rotatable internally screw threaded adjusting sleeve or nut 58, which operatively engages the free 55 end of said adjusting screw 54, and which may be turned to produce an adjusting movement of the free end of said contact arm 52 either toward or away from the thermostatic contact arm 55, as occasion 60 may require. Threaded on the outer end of said bushing 57 is a cover cap 59, which both closes over said adjusting sleeve or nut 58, and which may also serve, by frictionally engaging the head flange 58' of the latter against the end of the bushing 57,

to lock the adjusting sleeve or nut 58 in position to which it has been turned.

Suitably supported within said top-casing 10, above the iron body, is an electrical condenser 59' of any suitable form.

The main heating unit 6, for heating the body of the iron, is electrically connected through the condenser 59 and thermostatic switch or cut-out to the positive and negative plugs or terminals 38 and 39 as follows.

Connected with the positive plug or terminal 38, by engaging one end between washers 44 on the bolt 40 thereof, is a conductor 60 which leads to and is electrically connected with the fixed end of said adjustable contact

arm 52, through which the current passes to the mutually engaged contact buttons 53 and 56 into the thermostatic contact arm 55.

Electrically connected with the rear or fixed end of said thermostatic contact arm 55 is a conductor 61 which leads to and is electrically connected with the positive pole 62 of the condenser 59'.

Electrically connected with the negative pole 63 of the condenser 59' is a conductor 64 which leads to and is electrically connected with the positive pole of the electric heating unit 6.

Connected with the negative pole of said electric heating unit 6 is a conductor 65 which leads to and which is electrically en-

gaged with the negative plug or terminal 39 by connecting its outer extremity between washers 44 of the bolt 40 engaged with said negative plug or terminal 39.

The electrical circuits above described will be readily understood from an inspection of the wiring diagram shown in Figure 3 of the drawings, from which it will be clear

that the thermostatic switch or cut-out, condenser, and heating unit 6 are connected in

series between the positive plug or terminal 38 and the negative plug or terminal 39.

The iron is operatively connected with a source of electrical energy by feed wires suitably engaged or coupled with the plugs or terminals 38 and 39 by any desired contact making or coupling means (not shown),

as will be well understood by those skilled in the art.

In operating the novel construction of iron, when the same is connected with a source of electrical energy, the current will pass through the normally closed thermostatic switch and through the condenser to the main heating unit 6, whereby the iron

body is heated, while at the same time, by the established shunt circuit, the heating element or unit 34, serving the secondary steam generator at the heel of the iron, is con-

stantly or uninterruptedly operated while the iron is in service, regardless of the intermittent delivery of current to the main heating element or unit 6, so that sufficient

heat is constantly applied to said secondary steam generator at all times. Since it is de-

100
105
110
115
120
125
130

sirable that the heat applied to the body of the iron should not become excessive, but rather should be maintained at steady temperature of an approximately fixed predetermined degree, the thermostatic regulator or control switch or cut-out is provided to automatically control or regulate the operation of the main heating unit 6 so as to maintain the heat of the iron at the desired degree of temperature. The operation of the thermostatic regulator or control switch is such that the contact arms are normally engaged in circuit closing position, so that current is delivered through the heating unit 6. In the event the heat of the iron exceeds the desired predetermined temperature, the excessive heat tends to expand the bi-metal thermostatic contact arm 55, which by reason of the different coefficients of expansion possessed by its metallic component parts, is thereupon flexed or bent in a direction tending to remove its contact button 56 from circuit closing engagement with the contact button 53 of the adjustable contact arm 52, thus breaking the circuit through the heating unit 6. The supply of heat to the iron being thus interrupted, the temperature of the body of the iron drops again to the desired degree, and the thermostatic contact arm 52 contracts, and thus returns to normal contact making relation to the regulator contact arm 52, again renewing the supply of heat producing current through the heating unit 6, until the heat again becomes excessive, and a repetition of the above described operations ensues.

When the iron is in operation, steam is delivered from a suitable source of supply through the flexible steam conduit 23 to the steam intake pipe 20, and thence into the chamber 19 of the combined water trap and secondary steam generator. The steam thus delivered into the chamber 19 finds exit therefrom through the steam discharge pipe 26, discharge orifice 25 and thence into the steam distributing member 29, trap member 31, and steam chamber 3 of the iron body 1, whereupon, as the operator manipulates the iron to press goods, the steam from the chamber 3 will be extravasated through the vents 4 in the pressing face of the iron in contact with the goods being pressed, whereby the goods are sufficiently damped to assure rapid and complete smoothing out of all wrinkles, etc., in a manner well understood by those familiar with such operations.

Any condensation of steam occurring in the steam conduit 23 will be trapped in the lower end of the chamber 19 of the combined water trap and secondary steam generator, and the continuously operating electric heating unit 34 connected with the latter provides uninterrupted heat sufficient to reconvert the trapped water to steam, which

will thereupon again join the flow of live steam passing out of the chamber 19 through the discharge pipe 26, and thence, in the manner above described, into the steam chamber 3 of the body 1 for extravasation 70 through the vents in the pressing face of the latter.

Since, by the thermostatically controlled main heating unit 6, the iron body is maintained at an approximate predetermined 75 temperature, the steam delivered into the steam chamber 3 is guarded against undue temperature drop, so that condensation thereof within the steam chamber 3 and steam distributing means within the latter is 80 prevented, while at the same time excessive temperature rises likely to superheat the steam is likewise prevented, and excessive steam pressure both within the iron, and as to the steam extravasated are not permitted 85 to occur. Such prevention of condensation is important, since it obviates likelihood of water being discharged through the pressing face of the iron with consequent likelihood 90 of staining the goods to which the iron is applied. The prevention of excessive steam pressure is not only important from the standpoint of safety, but also because if steam at excessive pressure is discharged 95 through the vents 4 of the pressing face of the iron it is quite likely to perforate the goods being pressed to a damaging degree. It will be understood that when the iron is idle, any condensation in the steam distributing member 29 will be caught or trapped 100 in the trap member 31, and there held until the iron is again put in use, whereupon the heat imparted to the latter will reconvert the condensation to steam, which will be discharged into the steam chamber 3 as the 105 iron is used.

It will be understood that in a simple form of iron, the combined water trap and secondary steam generator above described, together with the electric heating unit therefor may be omitted, and steam from a primary source delivered directly through the distributing member 29, and its water trap 31, into the steam chamber 3. In such case 110 the advantages of my novel arrangement and construction of thermostatically controlled electric heating unit to which attention has been directed, are in no way effected, and I, therefore, deem this invention, 115 as described and hereafter claimed, to include within its scope an iron so constructed.

I am aware that some changes, other than those above indicated, may be made in the general arrangements and combinations of the various devices and parts, as well as in the details of the construction of the same, without departing from the scope of my present invention as described in the foregoing specification, and as defined in the appended claims. Hence, I do not limit my 120 125 130

invention to the exact arrangements and combinations of the devices and parts as set forth in the foregoing specification, nor do I confine myself to the exact details of the construction of said parts as illustrated in the accompanying drawings.

I claim:—

1. In a pressing appliance, an iron body having an internal steam chamber, said body having a plurality of steam vents leading from said steam chamber to the pressing face thereof, means for introducing steam into said steam chamber, an electrical heating means for supplying heat to said iron body, an electrical thermostatic control means in circuit with said heating means, and means for coupling said thermostatic control means and heating means with a source of electrical energy. 10

2. In a pressing appliance, an iron body having an internal steam chamber, said body having a plurality of steam vents leading from said steam chamber to the pressing face thereof, means for introducing steam into said steam chamber, an electrical heating means engaged with said iron body to supply heat thereto, a normally closed electrical cut-out provided with a thermo-expansive circuit breaking contact in circuit with said heating means, and means for coupling said cut-out and heating means with a source of electrical energy. 20

3. In a pressing appliance, an iron body having an internal steam chamber, said body having a plurality of steam vents leading from said steam chamber to the pressing face thereof, a combined water separator and secondary steam generator mounted on said iron to receive steam from a primary source and deliver the same to said steam chamber, a main electrical heating means engaged with said iron body to supply heat thereto, a second electrical heating means engaged with said combined water separator and secondary steam generator to directly supply heat thereto, and means for coupling said respective heating means with a source of electrical energy. 30

4. In a pressing appliance, an iron body having an internal steam chamber, said body having a plurality of steam vents leading from said steam chamber to the pressing face thereof, a combined water separator and secondary steam generator mounted on said iron to receive steam from a primary source for delivery to said steam chamber, a second water separator means within said steam chamber through which steam passes from said combined separator and generator into the interior of said steam chamber, a main electrical heating means engaged with said iron body to supply heat thereto, a normally closed electrical cut-out provided with a thermo-expansive circuit breaking contact in circuit with said main heating means, a second electrical heating means engaged with said combined water separator and secondary steam generator to directly supply heat thereto, and means for coupling said cut-out and main heating means with a source of electrical energy, said second electrical heating means being electrically connected in shunt circuit with said coupling means. 40

5. In a pressing appliance, an iron body having an internal steam chamber, said body having a plurality of steam vents leading from said steam chamber to the pressing face thereof, means for introducing steam into said steam chamber, an electrical heating means engaged with said iron body to supply heat thereto, a normally closed electrical cut-out in circuit with said heating means comprising an adjustable contact and a thermo-expansive contact, means for adjusting said adjustable contact toward or away from said thermo-expansive contact, and means for coupling said cut-out and heating means with a source of electrical energy. 50

6. In a pressing appliance, an iron body having an internal steam chamber, said body having a plurality of steam vents leading from said steam chamber to the pressing face thereof, means for introducing steam into said steam chamber, an electrical heating means engaged with said iron body to supply heat thereto, a normally closed electrical cut-out in circuit with said heating means comprising an adjustable contact and a thermo-expansive contact, means for adjusting said adjustable contact toward or away from said thermo-expansive contact, and means for coupling said cut-out and heating means with a source of electrical energy, said second electrical heating means being electrically connected in shunt circuit with said coupling means. 60

7. In a pressing appliance, an iron body having an internal steam chamber, said body having a plurality of steam vents leading from said steam chamber to the pressing face thereof, means for introducing steam into said steam chamber, an electrical heating means engaged with said iron body to supply heat thereto, a normally closed electrical cut-out in circuit with said heating means comprising an adjustable contact and a thermo-expansive contact, means for adjusting said adjustable contact toward or away from said thermo-expansive contact, and means for coupling said cut-out and heating means with a source of electrical energy, and an electrical condenser in series between said heating means and cut-out. 70

In testimony, that I claim the invention set forth above I have hereunto set my hand this 15th day of October, 1924.

CHARLES A. BREWER.

In testimony, that I claim the invention set forth above I have hereunto set my hand this 15th day of October, 1924.

CHARLES A. BREWER.
